(57) CLAIM

The ornamental design for an auricular thermometer, as shown and described.

DESCRIPTION

FIG. 1 is a top, front and side perspective view of a auricular thermometer showing my new design;

FIG. 2 is a front elevational view thereof;

FIG. 3 is a side elevational view thereof from the left of FIG. 2;

FIG. 4 is a side elevational view thereof from the right of FIG. 2;

FIG. 5 is a side elevational view thereof;

FIG. 6 is a top plan view thereof;

FIG. 7 is a bottom plan view thereof; and,

FIG. 8 is a view similar to FIG. 1 but showing the parts in a different position.
